UNITED STATES PATENT OFFICE.

ALLISON J. THOMPSON, OF CLEVELAND, OHIO.

LAMP-HANGER STRUCTURE.

Application filed January 24, 1925. Serial No. 4,503.

This invention relates to improvements in lamp hanger structures of the type comprising an upper stationary hanger member adapted to be mounted at an elevated point and a lower lamp-carrying hanger member adapted for releasable latching engagement therewith. The lower hanger member has attached thereto a suitable chain or cable by means of which it may be lowered to the ground or floor for the inspection, cleansing or repair of its parts, particularly the lamp and thereafter raised to latching engagement with the upper stationary hanger member.

Lamp hanger structures of this type are used in multitudinous places, such as along streets and above machinery in mills and shops, and it is often extremely inconvenient, if not impossible, to clean or repair the lamp or other parts of the lower hanger member at the place where it is lowered, due to traffic in the case of streets, and machinery and the like in the case of mills and shops, or because of insufficient illumination, or for other reasons. Moreover, the attendant darkness often prevents the performance of other work in the darkened area and when the repair or cleaning of the lamp or other parts of the lower hanger member requires considerable time, a material aggregate financial loss results.

The object of the present invention is to improve lamp hanger structures of the class described by the provision of a lower hanger member in which the illuminating lamp and the associated contact member or members connected thereto may be easily and almost instantaneously removed from and applied to said lower hanger member and without disturbing the wiring connection of said lamp and contact members. A dirty or improperly working lamp and the contact members therefor, which may be in the same condition, may be readily removed from the lowered lower hanger member and another lamp and other contact members, in clean and proper working condition, quickly substituted therefor. The illumination of the region or area of any lamp is, therefore, cut off for a few minutes only, so that the time of nearby workmen is not lost and the removed lamp and contact members may be

conveniently and safely cleaned or repaired where there is sufficient room, illumination and time and where there are proper tools or parts, if such are needed.

Further objects of the invention are in part obvious and in part will appear more in detail hereinafter.

In the drawings, Fig. 1 is a vertical sectional view of a lamp hanger structure embodying the present invention; Fig. 2 is a cross sectional view thereof on the line 2-2, Fig. 1; Fig. 3 is a detail sectional view on the line 3-3, Fig. 2; and Fig. 4 is a detail view of a detached lamp and one of its contact members.

The general type of lamp hanger structure illustrated in the present application is substantially the same as that shown in my co-pending application, filed February 24, 1923, Serial No. 620,802, to which reference may be had for a clearer understanding thereof, if desired.

The upper hanger member comprises a sheave housing 1 provided with laterally extending ears 2 by means of which the upper hanger member is supported at an elevated point. Journalled within this housing is a sheave 3 over which travels a chain 4 to which is attached the lower hanger member later to be described. Secured to the base of said housing by the screws 5 is a depending canopy member 6 within the central portion of which is secured, by these same screws 5, a slotted tubular member 7 provided on opposite sides of its slot with suitable latch receiving notches 7a.

Secured to the top wall of the canopy member by screws 8 are a pair of depending insulator blocks 9, each of which has anchored therein the upper end of a screw bolt 10, upon the lower end of which is mounted a suitable contact member 11. Suitable washers are provided for each contact member, such as the fibre washer 12 and the pair of brass washers 13 between which one of the contact lead wires 14 is clamped.

The lower hanger member comprises a hollow tubular stem 15 through which extends the chain 4, said stem being secured upon one end of said chain by the chain washers 16 which lie within the stem chamber 17. Pivotaly mounted upon the upper

end portion of this stem is a latching dog 18, which is adapted for latching engagement with the notches 7^a of the upper hanger tubular member 7, within which tubular member said stem is adapted to slidably engage. The two hanger members are latched together by a pull on the chain 4 so as to raise the latching dog of the lower hanger member above the slot notches 7^a of the upper hanger member; then upon slowly lowering the lower hanger member, the latching dog thereof will drop into said notches. To unlatch the hanger members, a slow pull on the chain 4 raises the latching dog out of said notches and a quick release of the chain causes the dog to drop down past said notches. When so unlatched from the upper hanger member, the lower hanger member may be readily lowered by the chain 4 to the floor or ground, for inspection, cleansing or repair purposes, and thereafter raised to latching engagement with the upper hanger member, as will be readily understood.

25. Co-operating with the two upper contact members are the contact members of the lower hanger member, which lower contact members are of like construction so that a description of one will suffice for both. Each 30 of said lower contact members includes an upper portion 20 having a convex upper contacting surface to properly contact with the contacting surface of one of the upper contact members. This upper contact portion 20 is held in the recess of an upper insulator block 21 by a screw bolt 22 having its curved head countersunk in said contact portion, said bolt 22 serving also to secure to said upper insulator block a lower insulator block 23 of like construction and size.

40. Each of the lower contact members is mounted upon a suitable support which is adapted for convenient and almost instantaneous application to and removal from the lower hanger member. Preferably, said contact supports are of resilient material to enable the contact members to have sufficient movement relative to the lower hanger member to properly engage the upper stationary contact members when the upper and lower hanger members are latched together. In the specific embodiment here illustrated, each of the contact supports is in the form of a resilient wire 24, bent into substantially 50. U-shape with the outer curved, converging end portions 25 thereof clamped in suitable grooves 26 in the contiguous faces of the insulator blocks of one of the contact members. The inner end portion 27 of each of 55. these contact supporting members is adapted to be hung over an upwardly extending lug or projection 28 of the lower hanger stem, said projections being formed on opposite sides of said stem, preferably integral therewith. In the present embodiment, these

contact supporting members are maintained in substantially horizontal position and preferably at the base of the projections 28 thereof by coils 29, each of the contact supporting members being here provided with 70 two coils. These coils engage the front face of the stem projections 28 and not only maintain the contact supporting members in such horizontal position but also materially assist in giving said members sufficient 75 resiliency to enable the contacts mounted thereon to properly engage the upper contacts when the upper and lower hanger members are latched together. The mounting of the contact supporting members upon 80 the projections 28 of the lower hanger member is, of course, firm or secure enough to prevent the accidental escape of said contact supporting members during raising and lowering movement of the lower hanger member. When the upper and lower hanger members are latched together with the lower contacts engaging the contacts of the upper hanger member, the supporting wires for 85 the lower contacts cannot be lifted and thereby escape.

As clearly shown in Fig. 4, the inner end portion of each of the lower contact supporting members is formed with a suitable opening 30 to receive a stem projection 28, which enables the contact supporting members to be easily, simply and quickly hung upon and freely lifted from the lower hanger stem.

100 Threaded to the lower end of the lower hanger stem 15 is an outlet connector member 31 to the lower hollow portion 31^a of which is threaded the illuminating lamp 32, which lamp may be of any suitable size and design. Suitably connected to said lamp are a pair of lead wires 33 which pass up through the tubular lamp connecting portions 31 of member 30 and then separate, one wire passing out through each of the two lateral passages 34 of said connector member. The upper ends of these lead wires are suitably attached to the lower contact members, such as by being clamped between washers 35 which are held against the lower insulating blocks 23 by the screw bolts 22.

110 With the present improved lamp hanger structure, the lamp of the lower hanger member need not be repaired or cleaned at the place where the lower hanger member is lowered with the disadvantages above mentioned, but the supporting members upon which the lower contacts are mounted may be readily and quickly lifted from the projections 28 of the lower hanger stem, after 115 which the connector member 30, to which is attached the lamp 32, may be readily unscrewed and removed from said stem, all without disturbing the wire connections between the lamp and the lower contact members. Another connector member having a 120

clean and properly working lamp equipped with a set of contact members electrically wired thereto may be readily screwed into the lower hanger stem and the supporting members of said other contacts quickly hung upon the projections 28 of the said stem, all without disturbing the wire connections of the lamp and contact members. The removed lamp and contact member may then be taken for cleansing or repair purposes to a place where it is safe and where there are suitable facilities therefor. The removal of the dirty or improperly working lamp and contact supporting members and the substitution of another lamp and other contact supporting members, in clean and proper working condition, require but a few minutes so that the period of non-illumination and the aggregate time loss are negligible.

20 What I claim is:

1. In a lamp hanger structure, a lamp carrying hanger means provided with an upwardly extending projection, an electric contact for the lamp of said hanger means, and a support for said contact provided with an opening to receive the projection of said hanger means, whereby said support may be hung upon said hanger means, the removal of said contact support from said hanger means being effected solely by lifting movement of said contact support and without the manipulation of a screw, nut or the like.

2. In a lamp hanger structure, lamp carrying hanger means provided with an upwardly extending projection, an electric contact for the lamp of said hanger means, and a support for said contact provided with an opening to receive the projection of said hanger means, whereby said contact support may be hung upon said hanger means, said contact support being provided with means co-operating with said hanger means for maintaining said support in a position substantially normal to the longitudinal axis of said hanger means when said support is hung upon the projection of said hanger means, said support being removable from said hanger means by simple lifting movement of said support and without the manipulation of a screw, nut or the like.

3. In a lamp hanger structure, lamp carrying hanger means provided with an upwardly extending projection, an electric contact for the lamp of said hanger means, and a support for said contact provided with an opening to receive the projection of said hanger means, whereby said contact support may be hung upon said hanger means, said contact support being provided with integral means co-operating with said hanger means for maintaining said support in a

position substantially normal to the longitudinal axis of said hanger means when said support is hung upon the projection of said hanger means, said support being removable 65 from said hanger means by simple lifting movement of said support and without the manipulation of a screw, nut or the like.

4. In a lamp hanger structure, lamp carrying hanger means provided with an upwardly extending projection, an electric contact for the lamp of said hanger means, and a support for said contact provided with an opening to receive the projection of said hanger means, whereby said contact support may be hung upon said hanger means, 70 said contact support being provided with a resilient coil co-operating with said hanger means for maintaining said support in a position substantially normal to the longitudinal axis of said hanger means when said contact support is hung upon the projection of said hanger means, the resilient coil of said support also affording a resilient mounting for said contact, said contact support being removable from the projection of said hanger means by simple lifting movement 75 of said support and without the manipulation of a screw, nut or the like.

5. In a lamp hanger structure, an upper 90 hanger member, a lamp carrying hanger member removably securable therewith, contact members secured on said upper hanger member, upwardly extending projections on said lamp carrying hanger member, contact supports mounted on said projections and removable therefrom by simple lifting movement, insulating means on said contacting supports, and contact members carried by said insulating means and arranged for 95 engagement with the contact members of said upper hanger member.

6. In a lamp hanger structure, an upper hanger member, a lamp carrying hanger member removably securable therewith, contact members secured on said upper hanger member, upwardly extending projections on said lamp carrying hanger member, contact supports mounted on said projections and removable therefrom by simple lifting movement 100 and having resilient convolutions abutting the base portions of said projections, insulating means on said contact supports, and contact members carried by said insulating means for wiping engagement with the contact members of said upper hanger member, 105 said wiping being generally arcuate about said convolutions.

In testimony whereof I hereby affix my signature.

ALLISON J. THOMPSON.
